INDIRECT LIGHTING FIXTURE EMPLOYING ULTRAVIOLET AND INCANDESCENT LAMPS

Leroy C. Doane, Meriden, Conn., assignor to The Miller Company, Meriden, Conn., a corporation of Connecticut

Application January 15, 1931, Serial No. 508,837

10 Claims. (Cl. 240—78)

The present invention relates to indirect lighting fixtures employing ultraviolet or glow lamps and incandescent lamps, and is more particularly directed toward lighting fixtures adapted to employ the same reflecting elements for downwardly and outwardly directing the light from both the ultraviolet and the incandescent lamps. To the eye the fixture illuminated appears the same (except for intensity of light) when both types of lamp are lighted or when one only is used.

The present invention contemplates a fixture adapted to employ a pendant or substantially pendant glow lamp, such as the mercury arc glow lamp, and wherein a number of upwardly extending incandescent lamps, together with the glow lamp, are shielded or screened by reflecting means adapted to upwardly direct light from both types of lamps onto a single reflecting surface forming, what may be termed, an artificial ceiling adapted to distribute both ultraviolet and visible light.

The invention also contemplates the utilization of a small amount of the light from the glow lamp or the incandescent lamp for illuminating the under surfaces of the reflecting means above referred to.

The invention also contemplates an improved fixture arranged for both types of illumination wherein the parts are arranged for convenience in relamping, cleaning and disassembling.

A further object of the invention is to provide a design for a fixture for totally indirect lighting in which the light controlling parts are susceptible of interchangeable use with all the lamps of the incandescent type or with one of the lamps of the glow type.

Other and further objects of the invention will appear as the description proceeds.

The accompanying drawing shows, for purposes of illustrating the present invention, one form in which it may take form, it being understood that the drawing is illustrative of the invention rather than limiting the same.

In the drawing:

Figure 1 is a side elevational view of a lighting fixture with parts in section;

Figure 2 is a top plan view of the lower reflector;

Figure 3 is a section taken on the line 3—3 of Figure 1; and

Figure 4 is a diagrammatic side elevational view.

In the form of construction shown in Figure 1 the fixture is supported from above by a rod or pipe 10 secured to a cross strap 11 by a nut in-

icated at 12. This cross strap 11 supports a transformer 13. A cross strap 15 is secured to the lower side of the transformer and this cross strap carries a tubular socket cover 16 and lamp socket 17 of the type adapted for holding a 5 mercury vapor glow lamp indicated at 18.

The end of the socket cover 16 is threaded as indicated at 19 and a ring 20 is threaded onto the socket cover. The ring 20 supports an upwardly and outwardly flaring sheet metal reflector 50, 10 preferably made of aluminum having an oxidized surface. This reflector may be made of two stampings 50a and 50b, as indicated, and is adapted to extend upwardly and outwardly to provide a comparatively large artificial ceiling for 15 the fixture. It may be mounted directly against the ceiling if desired. It may be solely supported by the ring 20 so as to be easily removable for shipment.

The stamping 50 is provided with three downwardly and outwardly extending legs 51, more or less ornamental in shape. These legs are secured to a reflecting member 52, preferably in the form of an aluminum casting, shaped as indicated in Figures 1 and 2. This casting has a 25 central, downwardly extending pocket 53, preferably provided with a removable sheet metal aluminum liner or reflector 54 having an oxidized surface to upwardly reflect light received from the glow lamp. The casting 53, as here shown, 30 has three pockets 55. These pockets, as well as the central pocket 53, have openings as indicated at 56. Straps 57 extend downwardly underneath these openings, as shown. The three 35 straps underneath the openings 56 are adapted to carry lamp sockets 58 as indicated. These lamp sockets are concealed by ornamental covers 59 spaced slightly from the casting, as indicated, and adapted to upwardly reflect a small amount of light from the incandescent lamps L 40 so as to illuminate the outside of the outer pockets by stray light. The strap 57 under the center opening 56 is secured to a slightly larger bell-shaped cover member 60 which is adapted to receive a small amount of stray light from the glow 45 lamp transmitted through the openings 61 in the reflector 54 to thereby illuminate the under surface of the casting 52.

In order that the lower reflector may be readily lowered to permit access to the glow lamp, as well as to facilitate removing the incandescent lamps and cleaning the reflecting surfaces, the lower ends of two of the arms 51 are preferably secured to the casting 52 in a readily detachable manner. Screw eyes 62 are threaded into the 55

lower casting. They carry wire rings 63 adapted to receive the lower ends 64 of the supporting legs. The arrangement permits holding the parts in suspended position, as indicated in full lines in 5 Figure 4.

The wiring of this fixture may include a pull chain switch 70 supported from the transformer and having two circuits, one of which controls the current for the transformer and glow lamp, 10 while the other controls the current for the incandescent lamps. The incandescent lamp circuit may include a convenience outlet indicated at 71, an attachment plug cap 72, and a length of wire indicated at 73 which extends downwardly 15 through a suitable hole in the stamping 50 and underneath the supporting strap 51. The lower ends of the cord 73 are provided with receptacles 74 adapted to be received on pins 75 secured to the casting 52 and connected to the various lamp 20 sockets for the incandescent lamps. The arrangements above described make it possible to disconnect the casting 52 and its lamps both electrically and mechanically from the support.

It is, of course, obvious that one can omit the 25 incandescent lamps and associated parts where a single ultraviolet source is desired and that the same arrangement of light controlling parts may be used with a centrally disposed incandescent lamp where ultraviolet light is not required but similarly appearing fixtures are 30 desired.

Certain features of construction shown herein are claimed in my application for Direct lighting fixtures employing ultraviolet and incandescent 35 lamps, Serial No. 508,838, filed concurrently herewith.

I claim:

1. A lighting fixture comprising a fixture body having a central upwardly opening pocket and 40 a plurality of outer upwardly opening pockets, a reflector extending upwardly and outwardly from above the central pocket, the outer pockets having openings therein, upwardly opening lamp sockets supported below said openings, lamp 45 bulbs carried in said sockets with their light sources in the pockets, socket covers about the sockets and spaced from the lower side of the plate to allow stray light to escape and illuminate the lower side of the plate, and an additional 50 light source in the central pocket, the pockets acting to screen off the light sources and redirect light upwardly onto the reflector.

2. A lighting fixture comprising a fixture body having a central upwardly opening pocket and 55 a plurality of outer upwardly opening pockets, a reflector extending upwardly and outwardly from above the central pocket, light sources in each of said pockets, the pockets acting to screen off the light sources and redirect light upwardly 60 onto the reflector, the central pocket having an opening therein, and a shade supported below the central pocket in a position to reflect light onto the outside of the central pocket to illuminate the same.

65 3. A lighting fixture having a single upwardly and outwardly flaring reflector symmetrical about a vertical axis, a single axially disposed lamp below the reflector, the reflector being concave to incident light to widely spread the light, a plurality of off center lamps adjacent the axially disposed lamp, a reflector for upwardly reflecting light from all the lamps, the reflector having openings to permit the escape of light downwardly, and supplemental reflectors below the open-

ings for returning this light upwardly to illuminate the outside of the reflector.

4. A lighting fixture comprising a lamp bulb, a downwardly dished reflector below the bulb and extending above the light source for screening off the light source and reflecting light upwardly, a reflector flaring upwardly and outwardly from adjacent the bulb, a plurality of lamp bulbs supported below the flaring reflector and screening and reflecting means for screening off the plurality of lamps and reflecting light therefrom upwardly onto the flaring reflector. 10

5. A lighting fixture comprising an upper reflector symmetrical about a vertical axis and flaring upwardly and outwardly from adjacent said axis, a lower reflector member having a pocket below the center of the upper reflector and a plurality of off center pockets, means for detachably supporting the member from the upper reflector and carrying a lamp in the central pocket, 15 a plurality of lamp sockets supported from the member, and lamps in the latter mentioned sockets carrying their light sources in the outer pockets, the upper reflector receiving direct and reflected light from the light sources and the member. 20

6. A lighting fixture comprising an upper reflector symmetrical about a vertical axis and flaring upwardly and outwardly from adjacent said axis, a lower reflector member having a pocket 30 below the center of the upper reflector and a plurality of off center pockets, mounting means for supporting the lower reflector member in horizontal position or in hanging position, a central socket in fixed relation to the upper reflector and 35 carrying a lamp in the central pocket, and a plurality of lamps carried in lamp sockets secured to the lower reflector member with their light sources in the outer pockets, the latter mentioned lamps being held underneath the upper reflector 40 and concealed from view when the lower reflector member is horizontal and all the lamps being accessible when the lower reflector member is in hanging position.

7. A lighting fixture comprising a central support, a downwardly opening lamp socket at the lower end of the central support, a pendant bulb therein, an upwardly and outwardly flaring reflector adapted to receive upwardly directed light from the pendant bulb, supporting means for the 45 reflector, a lower reflector supported from the upper reflector and spaced therefrom to accommodate the pendant bulb and reflect light therefrom onto the upper reflector, the lower reflector also carrying a plurality of lamp bulbs and reflecting light therefrom onto the upper reflector. 55

8. A lighting fixture having a substantially pendant glow lamp adapted to emit both ultraviolet and visible light, a plurality of incandescent lamps, reflecting means below each of the lamps for screening the same and reflecting light therefrom upwardly, and a single reflector superposed above the lower reflector and receiving direct and reflected light from both types of lamps and returning the same downwardly, the lower reflector being supported by means which permit lowering it to give access to all the lamps. 60

9. In an indirect lighting fixture, a fixture body having a central and a plurality of outer pockets, all the pockets being upwardly opening and apertured, lamp sockets supported below the outer pockets, lamp bulbs in the sockets, the lamp bulbs extending through the apertures in the pockets so that the bulbs are in the pockets so that the pockets reflect light upwardly, and covers 70 75

- for the sockets and lower parts of the lamp bulbs, the covers being spaced from the reflector to permit stray light to illuminate the outside of the plate.
- 5 10. An indirect lighting luminair comprising a centrally disposed light source, a reflector below the light source for intercepting substantially all the light emitted in the lower hemisphere and directing it upwardly and outwardly for indirect lighting, a plurality of independent light sources mounted outside of the said reflector, opaque

screens about said last mentioned light sources and the reflector for concealing the same and upwardly reflecting light from the last mentioned light sources for indirect lighting, said screens and reflector having openings to allow a small proportion of the light to pass downwardly, and supplemental screens for intercepting such light and returning it into the outside of the screens for illuminating the same.

LERoy C. DOANE.
